UNITED STATES PATENT OFFICE

JOSEPH O. JONES, OF KINGSVILLE, TEXAS, ASSIGNOR OF ONE-HALF TO JACOB L. GREGG,
OF KINGSVILLE, TEXAS

SHINGLE

Application filed February 28, 1930. Serial No. 432,157

This invention relates to new and useful improvements in shingles, and particularly to composition, asphalt, or other pliable shingles for roofing.

5 The principal object of the invention is to provide a roofing shingle of such construction that its lower free edge or corner can be effectively locked against displacement by the action of wind, rain or the like, and a further object is to provide a novel form of lock or fastener for said shingles whereby one row or series may be secured to another row or series.

Other objects and advantages will be apparent from the following description when taken in connection with the accompanying drawing.

In the drawing:

Figure 1 is a plan view of a portion of a roof equipped with shingles forming the subject-matter of the present invention.

Figure 2 is a perspective view, slightly enlarged, of the matter shown in Figure 1, showing the locking means.

25 Figure 3 is a perspective view of a portion of a shingle and a fastener or locking device carried thereby.

Figure 4 is a view looking toward the underside of the shingle portion shown in Figure 3 and more clearly disclosing the construction of the fastener or locking device.

Referring particularly to the accompanying drawing, and especially to Figures 1 and 2, it will be seen that a strip of shingles 10 consisting of two or more in a row or series, of diamond shape are arranged in a horizontal line, and have one or more connecting neck portions 11 between the adjacent side corners of the shingles. The corner of each shingle of a horizontal series, diametrically opposite to the connecting neck 11, is formed with a tab 12, of a width equal to that of the neck, but of a length one-half thereof, which is adapted to abut the tab of an adjacent pair of shingles to form a complete neck portion. The shingles are secured to the roof by driving two nails 13 through each neck portion, and one through each of the tabs, such nails being spaced a certain distance for a purpose which will presently appear herein.

The shingles are secured to the roof in courses or rows, so that the lower corner of each shingle overlaps the neck portion 11, or the abutting tabs of the next course below.

The locking member or device is formed from a single length of wire bent to provide a shingle engaging bill or stem portion 14 and a cross-head 15 at one end of the bill and projecting from opposite sides thereof, which latter includes end portions or bars having crimped or indent U-shaped keepers, seats or retaining portions 17 receiving and holding in position the ends of crossed members 18 forming an outer bar for said head, which ends of the crossed members forming the outer bar are bent to provide prongs or hooks 19 extending through the seats or keepers and interlocking therewith. These prongs or hooks are of a length to be passed through a shingle and bent inwardly toward each other across the end bars, the construction being such as to provide a firm connection between the fastener and the shingle to which it is applied and to provide a stem or bill which may be engaged with a neck portion or tabs of other shingles for securely uniting all said shingles together. By this construction of the fastener or locking device the cross-head is reinforced and, since the prongs are engaged with the seat 17, the cross-head will be strongly attached at its ends to the shingle and the locking device prevented from being bent out of its proper position. The locking member is applied to a shingle, by placing the head 15 against the lower face of the lower corner of the shingle, and pressing the tangs therethrough, and clinching the same on the opposite face of the shingle. In this position of the locking member, the stem portion 14 projects downwardly from the corner of the shingle. The operator grasps the stem, and bends the lower corner thereof beneath the shingle, along the line of the upper edge of the locking member, so that the stem then extends upwardly beneath the shingle. When the shingle unit is applied to the roof, the operator inserts the stem beneath the neck 11, or beneath a pair of tabs 12, between the attaching nails 13, and then drives nails in the necks and tabs of this course of 100

shingles, in the manner clearly illustrated in Figures 1 and 3.

Ordinarily, the free ends or lower edges of shingles of this character, are not attached to the roof, with the result that wind lifts such edges, causing the tearing of the shingles, and permitting entrance of rain, snow, and the like, therebeneath, and through the roof. With the present construction, the lower edges of the starting shingles are securely held in a flat position on the roof, and will resist the efforts of the wind to raise them, with the result that a perfect watertight roof is provided.

15 A starter strip is used at the eaves of the roof, and one form of this strip is shown at 23 as being elongated and rectangular, and on this strip the first row or course of shingles is laid. This form of strip is clearly shown in Figures 1 and 2, but other forms may be used.

What is claimed is:

25 A shingle anchoring device comprising a strand of wire bent intermediate its length to form a shingle engaging bill and a cross head at one end of the bill projecting from opposite sides thereof, end bars of the cross head being crimped to form inwardly extending seats, and end portions of the strand 30 forming an outer bar for said head being disposed in crossed relation to each other and having their ends bent to form prongs extending through the seats and of a length to be passed through a shingle and bent inwardly toward each other across the end bars.

35 In testimony whereof I affix my signature.
JOSEPH O. JONES.
